UNITED STATES PATENT OFFICE

CASSIUS JEFFERSON ASHBY, OF EVANSVILLE, INDIANA

EMBROIDERY OR RUG MACHINE

Application filed May 26, 1928. Serial No. 280,774.

This invention relates to an improved hand-operated machine for performing embroidery work or making rugs.

The object of the invention is to provide a simple, inexpensive, and efficient embroidery or rug making machine or appliance adapted to be operated by the hands of the user and designed to handle any kind of yarn, thread, carpet rags, or any goods of the string type and by which any kind of embroidery work or pile-rug work may be carried on.

The invention comprises a pair of reciprocating members provided with means by which they may be manipulated by the hands of the user, means interacting with them so that they will tend to travel in opposite directions to equal extents when manipulated and will be self-restoring, when released, to dispose in projected position the needle which is carried by one of said members, so that it is positioned to be pressed through the work, a thread pusher or plunger being carried by the other member, the needle being adapted to carry the thread or yarn through the backing or burlap or linen or other piece of goods on which the embroidery is to be provided or which is to serve as a backing for the rug, the plunger co-operating with the needle to form the loops or pile.

A practical embodiment of the invention is set forth hereinafter and is shown in the accompanying drawing in which:

Figure 1 is a side elevation of the machine when in normal position;

Fig. 2 is a similar view showing how the plunger or pusher forms the loop;

Figs. 3 and 4 illustrate diagrammatically the operation of the needle and plunger;

Fig. 5 is a detail view of the needle; and

Fig. 6 is a similar view of the plunger.

The needle-carrying and plunger-carrying operating members are shown at 1 and 2, respectively, there being provided suitable hand-holds or handles 3, 4 on said members whereby said members may be manipulated when grasped by the hands of the operator. The members 1, 2 have racks 5, 6.

There is a plate 7 which carries a pinion 8 that meshes with the racks 5, 6. A contrac-

tile coil spring 9 connects the plate 7 to the member 1. Means may be provided at 10 for regulating the tension of the spring 9.

A stirrup 11 carried by member 2, slides in a slot 12 in member 1, thus coupling the members 1 and 2 together. Bifurcated guides 13, 14 on the members, straddle the other member. The guide 14 will be in the form of a stirrup or loop to hold the ends of the members together so that the needle 15 and the plunger 16 will slide back and forth in close relationship to each other when the device is in use.

The needle 15 has the appearance of an ordinary pen point, being detachably connected to the member 1 at 16' and having an elongated eye 17' so that it will accommodate the usual threads, yarn, carpet rags, and other pieces of material of the string type.

The plunger 16 is secured at 17 to the end of the member 2, said plunger being a flat piece with a square lower end arranged to slide closely to the needle.

Figs. 3 and 4 illustrate diagrammatically how the needle forms alternate loops 18, 19 on opposite sides of the backing or burlap or other fabric 20 which serves as the body or backing for the embroidery or rug, loops being held by the binding action of the threads of the backing or burlap.

The thread, yarn, or piece of carpet rag appears at 21, being threaded through the eye 17'.

When operating the machine, the backing 20 is held in a suitable frame. If embroidery is to be provided, the backing or fabric 20 will be stretched over the usual small hoop or ring used in embroidery work. If a rug is to be made, the backing 20, which will be of burlap, will be stretched over a suitable frame.

The operator grasps the handles 3 and 4 and works them up and down which causes the needle 15 to penetrate the backing 20 to form the loops 18. The loops 18 are retained, as the needle rises, by the plunger 16. Thus, the loops 18 and 19 are formed on opposite sides of the backing 20 as the work progresses and any desired design or pattern.

may be carried out in making the article.

The racks 5, 6, pinion 8 and spring 9 tend to cause automatic restoration of the parts to the positions shown, generally, in Fig. 1, 5 to dispose the needle 15 in projected position, in readiness to be forced through the work when the device is manipulated. The racks and pinion also tend to cause an equal extent of movement in opposite directions 10 of the needle 15 and plunger 16.

Any suitable means may be provided for regulating the stroke of the needle and plunger so that loops of any desired height may be formed.

15 What I claim is:

1. In a rug making machine, the combination of a pair of reciprocating members having means by which they may be manipulated by hand, a needle carried by one of 20 said members, a plunger carried by the other member, said needle and plunger being adapted to form loops on a backing when the needle is provided with yarn, said members being slidably engaged with each other, 25 a plate, a pinion carried by said plate, a spring connecting the plate to one of the members, and racks carried by the members which engage with said pinion, whereby there is a tendency to automatically equalize the 30 extent of travel of the said plunger and needle when the said members are manually reciprocated in opposite directions.

2. In a rug making machine, the combination of a pair of reciprocating members having means by which they may be manipulated by hand, a needle carried by one of 35 said members, a plunger carried by the other member, said needle and plunger being adapted to form loops on the backing when the needle is provided with yarn, said members being slidably engaged with each other, a plate, a pinion carried by said plate, and racks carried by the members which engage 40 with said pinion, said racks and pinion tending to automatically equalize the extent of travel of the said plunger and needle when the said members are manually reciprocated in opposite directions.

45 In testimony whereof I affix my signature.

50 CASSIUS JEFFERSON ASHBY.
